UNITED STATES PATENT OFFICE

RANDOLPH CROMPTON, OF WORCESTER, MASSACHUSETTS

BLADE-WIPING RAZOR

Application filed July 20, 1929. Serial No. 379,774.

My invention relates to razors, especially that type known as safety razors, and aims to provide for such razor operatively related blade-cleaning and wiping means.

5 In the drawings illustrating one embodiment of the invention, by way of example, Fig. 1 is a side elevation of a blade-wiping razor, assembled;

10 Fig. 2 is a similar view of the holder or body portion, alone;

Fig. 3 shows the cleaning and wiping means, removed as for replacement or inspection; and

15 Fig. 4 is a view in elevation, with the razor head parts separated and the holder portion at right angles to its position shown in Fig. 1, indicating the manner of use in cleaning or wiping a blade.

The razor may be any standard or other 20 form. As illustrated it includes the tubular body, holder portion or handle 1, the guard 2, a blade 3, the head 4 with threaded boss 5 for reception in one end of said handle, and the closure element or handle cap 6, herein 25 having a knurled finger-grip as at 7 and a plug 8 fitting in the outer end of the handle.

In accordance with my invention I provide 30 means operatively associated with the razor whereby a blade, immediately after use, may be cleaned, dried, and replaced in readiness for subsequent use, without requiring the employment of any means aside from that forming a part of and carried by the razor itself. Thus I make it unnecessary to resort 35 to the use of a towel or other cloth or the like for cleaning the blade, avoiding the cutting and damaging of towels frequently complained of by housewives and others, as well as overcoming the other inconveniences 40 usually attendant on proper care of a blade.

In the illustrative embodiment of the invention, the wiping and cleaning means is sheathed in the razor handle or body portion.

As shown, the wiper proper comprises two 45 substantially cylindrical wiper elements 9, 9,

each supported on one leg of a staple or like U-shaped member 10. The free ends 10^x of the staple legs are removably but securely set in the plug 8.

These wiper cylinders 9, 9 may be of any suitable material, preferably somewhat absorbent, such as felt, absorbent paper, sponge or other rubber, or other wiping material. Their supporting means, the staple 10, is so constructed with respect to the wipers 9, 9, 55 that the latter are pressed tightly into contact with each other substantially throughout their lengths, and can not turn freely. The staple legs are separated slightly less than the distance between the axes of the two 60 wipers would be if the latter were merely laid side to side; thus the wiper elements are forced into engagement with each other or somewhat compressed, one against the other. This effect may be increased by so arranging 65 the openings in the plug 8 which receive the staple legs that the latter are made to converge toward the plug.

In cooperative relation with the wiper element, the razor holder or handle is provided 70 with blade receiving and guiding formations or slots 12, 12 whereby a blade requiring wiping may be entered and passed between the wipers in the manner illustrated in Fig. 4.

The manner of use of the wiper-equipped 75 razor will be readily understood from the foregoing, and particularly with reference to Fig. 4. Upon completion of a shaving operation, the blade is removed in the customary manner. It is then readily passed through the wiper one or more times, being guided by the slot formations 12, 12 in the razor body. Thus cleaned and dried it may be immediately reassembled in the razor, in instant readiness 80 for the next shaving operation.

85 The wiper may be withdrawn from its sheathed, operative position at any time by mere removal of the closure member 6, while preferably the U-shaped member 10 is likewise readily removable from the closure mem- 90

ber, for cleaning or replacement of the wiper means. If preferred, renewals for the latter may be supplied as a unit with the closure member or cap, or individual paper, felt or other members may be provided for ready positioning on the legs of the U-shaped member.

The razor of my invention, with self-contained wiper, is extremely compact and convenient, especially for use in travel. It ob-

10 viates damage to towels, and also makes unnecessary the special razor-cloths provided by many hotels. Following my invention the useful life of a blade may be substantially increased, by keeping it free from rust and other stains. Heretofore, with the ordinary razor, most users would not bother to clean or wipe the blade properly, because of the extra paraphernalia, time and trouble until

20 now necessitated.

My invention is not limited to the particular illustrative embodiment herein shown and described, its scope being pointed out in the following claims:

25 1. In combination, a tubular body adapted to support a razor head at one end, slot formations in the wall of said body in diametrically opposed relation, and a blade wiper within the body in position to wipe a blade passed

30 through said formations.

2. In combination, a tubular razor body or handle, a removable cap at one end, and a blade wiper projecting from said cap and receivable in the said body or handle.

35 3. In a device of the class described, a hollow body portion or handle, a pair of juxtaposed wiper elements supported therein, and formations in said body portion or handle whereby a blade may be passed between and in wiping relation to said wiper elements.

40 4. In combination, a supporting element, and non-abrasive blade wiping means operatively related to and supported by and at one end of said element in substantial parallelism therewith.

45 5. In a device of the class described, a tubular body portion or handle, and blade-wiping means supported in one end thereof, comprising opposed wiper elements adapted to engage and wipe the two faces of a blade passed between them.

50 6. In a safety razor, a handle element having a receiving portion, and non-abrasive blade treating means positioned in said receiving portion, said treating means being supported in position for use.

55 7. A tubular member having nonabrasive blade treating means therein, said member having cut-away portions whereby said means is operably accessible to a razor blade.

60 8. In combination, a tubular body adapted to receive blade-holding means at one end, a closure member at the other end, a U-shaped member removably projecting from the closure member, a cylindrical wiper member on

each leg of said U-shaped member in position to wipe the two faces of a blade passed between them, and blade-receiving and guiding slot formations in said body in a given diametral plane therethrough, the line of mutual contact or closest approach of said wiper members lying in said plane of the slot forma-

70

75 In testimony whereof, I have signed my name to this specification.

RANDOLPH CROMPTON.
